To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of this design consists of an ornament composed of a bunch of grapes with three leaves tied with a ribbon, as represented in the accompanying drawing. The ribbon is arranged in the form of a loop partly hidden behind the leaves, and the ends of the ribbon hang down on either side of the bunch

15 of grapes and intersect or cross each other beneath the bunch of grapes. These ornaments are arranged at regular distances apart over the surface of the paper and are printed in color or bronze of any desired color upon tinted paper of any desired color.

What I claim is—

20 The design for wall-paper herein shown and described.

25 Witness my hand this 30th day of September, 1892.
